G. SCHULTZ

DOOR FIXTURE

Filed June 26, 1922

Fig. 3.

Fig. 2.

UNITED STATES PATENT OFFICE.

GUSTAV SCHULTZ, OF MILWAUKEE, WISCONSIN.

DOOR FIXTURE.

Application filed June 26, 1922. Serial No. 571,094.

To all whom it may concern:

Be it known that I, GUSTAV SCHULTZ, a citizen of the United States, and resident of Milwaukee, in the county of Milwaukee and State of Wisconsin, have invented certain new and useful Improvements in Door Fixtures; and I do hereby declare that the following is a full, clear, and exact description thereof.

10 This invention pertains to door fixtures and more particularly to that type of fixture adapted to lock a hinged door in its opened position.

15 The primary object of the invention is to provide a simple and efficient device of the above character, adaptable to any form of swinging door, such as garage doors, and which is provided with yieldable means to prevent strain or jar upon the door, resulting from a sudden stop when the door is swung to its opened position.

20 A further object resides in the specific method of latching and releasing the lock, whereby a durable structure is obtained, 25 which is not subject to damage resulting from severe usage to which these devices are put.

25 With the above and other objects in view, which will appear as the description proceeds, my invention resides in the novel construction, combination and arrangement of parts, substantially as hereinafter described and more particularly defined by the appended claims, it being understood that such 35 changes in the precise embodiment of the herein disclosed invention may be made as come within the scope of the claims.

35 In the accompanying drawing, I have illustrated one complete example of the physical embodiment of the present invention constructed according to the best mode I have so far devised for the practical application of the principles thereof, and in which:

45 Figure 1 is a sectional view through the casing of a door, illustrating the door in its opened position and showing the invention attached thereto, parts of the latter being broken away to more clearly illustrate 50 the structural features.

55 Figure 2 is an elevational plan view of a door with the invention attached thereto, the casing being shown in section, and

Figure 3 is an enlarged detailed view of the latch mechanism. 55

Referring now more particularly to the accompanying drawing, the door casing is designated by the numeral 1 and has hinged thereto the door 2, to which is attached a bracket 3. Loosely pivoted on the bracket 60 for horizontal movement and slight vertical movement is a latch rod 4 provided on its under side with a notch 5 adapted to be engaged by the notched plate 6, through which the rod travels, and in order to prevent the latch rod 4 from sliding out of the latch plate as the door is swung open, the rod is provided, at its end, with a pin 7. 65

For the purpose of cushioning the door as it reaches its extreme outer position and thereby preventing a strain or jar on the same, the latch plate 6 is slidably secured to an attaching plate 8 secured to the top of the casing 1. Disposed between the latch plate and attaching plate is a coil spring 9 70 guided by the pin 10 passing through the downwardly extending ears carried by both latch members. 75

80 From the foregoing, it is obvious that as the door 2 is swung open, the latch plate 6 will be engaged either by the notch 5 in the latch rod, or by the pin 7, and the force of the door will be cushioned or absorbed by the spring 9, thus preventing a sudden stop or jar which often results from strain 85 on the hinges of a door, as well as damage to the door lights. 85

85 The pin 11, which serves as the pivot for the latch rod 4, is provided with a depending yoke 11', in which is pivoted a lever 12, one end of which is attached to the latch rod 4 by means of a bolt 13, while the other end is provided with a suitable chain or cable 14, for actuating the lever. When the door is in its opened position, as illustrated in Figure 1, and it is desired to release the lock, the chain 14 is pulled downwardly and through the lever 12 the latch rod will be raised to disengage the notch 5 from the latch plate 6 and permit the door to be 90 95 swung inwardly. 100

100 As previously stated, the latch rod 4 has a slight vertical pivotal movement, which is obtained by loosely mounting the pin 11 in the bracket 3. Particular attention is directed to the fact that the means, for re- 105

lieving the latch rod 4 to disengage it from the latch plate, is rigid with the pivoted end of the latch rod instead of being attached to the latch plate, as in most devices on the market at the present time. This insures a more durable structure and enables the latch rod to be pivoted on the door instead of the casing, while the latch plate is secured to the casing. This arrangement is very desirable, in that it permits attachment to the casing at a greater distance from the side of the casing than where the arrangement is reversed.

I claim:—

15 1. A locking device adapted to be attached to a swinging door and casing and comprising a bracket, a latch rod pivoted on said bracket and provided with a locking notch, a yieldable latch plate adapted 20 to engage said notch and cushion the door, and means for disengaging the rod from said plate.

25 2. A locking device adapted to be attached to a swinging door and casing and comprising a bracket mounted on said door, a latch rod pivoted on said bracket and provided with a locking notch, a yieldable latch plate secured to said casing and adapted to engage said notch and cushion the

door, and means adjacent the pivoted end 30 of the latch rod for raising and disengaging the same from the latch plate.

3. A locking device adapted to be attached to a swinging door and casing and comprising a bracket, a latch rod horizontally and vertically pivoted on said bracket and provided with a locking notch, a yieldable latch plate adapted to engage said notch and cushion the door, and a lever carried by the bracket for lifting the latch 40 rod out of engagement with the latch plate.

4. A locking device adapted to be attached to a swinging door and casing and comprising a bracket, a latch rod horizontally and vertically pivoted on said bracket 45 and provided with a locking notch, a yieldable latch plate adapted to engage said notch, a pivot pin carried by the bracket, and a lever carried by said pin, one end of the lever being secured to the latch rod and 50 the other end being provided with means for actuating the lever to lift the latch rod out of engagement with the latch plate.

In testimony that I claim the foregoing I have hereunto set my hand at Milwaukee, 55 in the county of Milwaukee and State of Wisconsin.

GUSTAV SCHULTZ.
